MULTIPLE TUBE PUMP

Clifford M. Peters, El Dorado, Ark.

Application May 1, 1936, Serial No. 77,368

4 Claims. (Cl. 103—179)

This invention relates to pumps having reciprocable plungers in which the seal between the plunger and the pump cylinder or barrel, is effected by a plurality of telescoping sleeves, this type of pump being particularly adapted for deep well pumping, as in the oil fields, where pumping, for economical reasons makes it advantageous to use casings, cylinders and discharge pipes of small diameter.

10 The primary object of the present invention is to make a pump of this type which is double acting and in which the effective discharge volume will be largely increased over other pumps of this type, and which will as nearly as possible reach a maximum capacity in a pump of this type for the particular size of casing used.

In accomplishing this purpose, I make use of double displacement pump chambers involving the employment of five tubes, two of which are 20 travelling or plunger tubes and three standing or cylinder tubes, one of these standing tubes forming the cylinder barrel, the particular arrangement accomplishing double displacement pump chambers which materially increase the 25 effective volume displacement per stroke.

The means by which the foregoing and other objects are accomplished and the manner of their accomplishment, will readily be understood from the following description, on reference to 30 the accompanying drawing, in which,—

Fig. 1 is a sectional elevation of the upper portion of my improved cylinder and plunger; and

Fig. 2 a similar section of the lower end of the same cylinder and plunger, it being understood that between these a considerable portion of the usual length of the tubes has been omitted.

Fig. 3 is a similar section of a modified form of the lower end of the pump, usable with the 40 upper end shown in Fig. 1.

Fig. 4 is a section taken on the line IV—IV of Fig. 3.

Referring now to the drawing in which the various parts are indicated by numerals; 10 is 45 a well tubing, to the lower end of which is secured, as by means of threads, a seating shoe 11, and which, after the shoe is secured, is lowered to the bottom of the well and immersed in the fluid to be pumped. The pump includes a cylinder assembly and an interlocking plunger assembly. The cylinder assembly comprises three spaced standing tubes 12, 13 and 14, the outer of which tubes 12, forms the cylinder barrel. The barrel 12 is secured at its lower end, as by a 50 threaded joint, to a standing valve body 15, to

which body the inner tube 14 is also secured as by threading. The upper end of the tube 14 has externally secured thereto as by welding, a sleeve 16 to which sleeve the tube 13 is similarly secured, and from which sleeve the tube 13 depends between the barrel 12 and tube 14. Secured to the lower end of the valve body 15 as by threads is a valve seat member 17. Supporting this seat member, is a tapered plug 18, which is adapted to be supported by a tapered seat 19 in the shoe 11, the joint between the tapered plug and its seat 19 cooperating to form an effective seal. 20 is a ball valve which cooperates with the seat 17 to form a standing valve, the ball being limited in its movement as by a transverse pin 21. 22 are openings through the tube 14 adjacent its lower end giving free communication into the lower pump chamber 23 between the barrel 12 and tube 14.

The pump plunger comprises a head 25 having a central opening 26 therethrough, the upper end of this head forming a seat for a ball valve 27, the head 25 and ball 27 forming a travelling valve. Secured to the upper end of the head 25, as by threading, is a cage 28 for the valve 27, the upper end of this cage having a threaded shank 29 to which the sucker rod 30 is secured. Secured to the head 25 as by threads and depending therefrom within the barrel 12 is an outer plunger tube 31. At the lower end of this tube a spacing sleeve 32 is inserted and secured as by welding, and to this sleeve is secured an inner plunger tube 33, which extends upward between the tubes 13 and 14 of the cylinder assembly. The lower end of the plunger formed by the tubes 31 and 33 and the interposed sleeve 32, forms an annular plunger which is moved upward and downward during pumping in the annular space or chamber 23 of the cylinder. Between the lower end of the cylinder tube 13 and the sleeve 32 is an annular chamber 35, and similarly between the tubes 13 and 14 of the cylinder, an annular chamber 36 is formed, both the chambers 35 and 36 decreasing on the up stroke of the plunger, and increasing on the down stroke thereof. At the upper end of the standing tubes is an upper pump chamber 37 which is supplied through the center passageway 38 of the standing tube 14.

In the modified form shown in Figs. 3 and 4 50 the well tubing 10A has secured at its lower end the shoe 11A which may be formed as before with a tapered seat, but which preferably is formed with an annular shoulder 40 on which is seated a sealing ring 41 which in turn supports 55

and is compressed to form a seal by an annular flange 42 on the pump assembly. The cylinder assembly of the pump comprises as before, a barrel tube 12A, an inner tube 14A which latter tube is a continuation of the tube 14 of Fig. 1, and as before, supports the third tube 13 of the same figure. Cooperating with the tubes 12A, 13 and 14A are plunger tubes 31 and 33 identical with those before described. 43 is a tubular member preferably forming a continuation of the barrel tube 12A. For purposes of construction the barrel tube 12A has been internally offset at its lower end to form a depending sleeve 44 of reduced diameter which is exteriorly threaded 15 and engages with interior threads on the upper end of the tube extension 43 to support the latter. The tube 43 is exteriorly enlarged to form the flange 42 hereinbefore mentioned and by means of which flange the cylinder assembly is 20 supported. At its lower end the tube 43 carries a standing valve preferably comprising a valve body 45 and cooperating ball valve 46. 22A are openings through the inner tube 14A into the chamber or space 23A between the inner and outer tubes 14A, 12A. Disposed within the outer tube 43 is an auxiliary standing valve of generally tubular form which comprises a tube 50 secured to the lower end of the tube 14A as by threads and depending therebelow. In the lower end of 25 this tube is secured as by threading, a valve body 51, which forms a seat for a ball valve 52. Disposed between the tube 50 and the tube 43 are oppositely disposed hub members 53 which may be integral with both the tube 50 and the tube 30 43, or may be secured to one or both thereof as by welding. Extending radially outward through the tube 50 and the hubs 53 and the tube 43 are passageways 54 which establish communication from the interior of the tube 50 to the exterior 35 of the tube 43 into an annular passageway 55 in the shoe 11A and thence upward through the passageway 56 between the outside of the tubes 43-12A and the interior of the tubing 10A. Immediately above the passageways 54 is a dia- 40 phragm or plug 57 sealing off the lower end of the inner tube 14A. 58 is a transverse pin limiting movement of the ball 52.

In constructing both forms of the device, I make use of cold drawn seamless steel tubes of 50 such relative diameters as to leave approximately .020 inch clearance separating each tube from its adjacent tube, the longer ones of these tubes under usual conditions being about 18 feet in length. By such construction I set up through 55 the skin friction of the liquid pumped the necessary resistance to leakage, and am enabled to dispense with the accurate machine work otherwise necessary to secure close fits. Such greater clearance also largely reduces the wear due to sand in 60 the liquid being pumped and greatly extends the useful life of the pumps. The plunger tube assembly and the cylinder tube assembly are brought together in working relation and are then secured to their respective valve bodies accom- 65 plishing an interlocked plunger-cylinder pump which may be lowered as a unit into the well, or removed therefrom.

In using either form of the pump the interlocked structure is secured to the sucker rod 30 and by means of the sucker rod is lowered through the tubing 10 until it comes to rest on the seat provided therefor in the shoe at the lower end of the tubing. Thereafter the sucker rods are connected to a usual or desired form of operating 70 mechanism and pumping may be begun.

In the forms shown in Figs. 1 and 2, on the up stroke the fluid is drawn in through the standing valve 17-18, and into the lower pump chamber 23, the bore 38 of the tube 14 and the upper pump chamber 37 which is at the upper end of the standing tube 13-14. On the down stroke of the pump the standing valve 17-18 closes and the fluid trapped in the lower chamber 23, and in the upper chamber 37 is discharged through the travelling valve 26-27, it being noted that the discharge volume is the sum of the inner area of the plunger tube 31 and the annular area of the chamber 23, multiplied by the length of stroke. The displacement volume not only being greater than the ordinary displacement volume by reason of the greater area of the upper displacement chamber 37, but in addition to this being augmented by the displacement volume of the lower annular chamber 23, the area of this latter chamber being a surprisingly large proportion of the total interior area of the outer standing tube or pump barrel. As an example, in a typical construction in which the pump is designed to be run in a well having 2½ inch tubing the outside diameter of the standing tube or pump barrel is held under usual practice to 2¼ inch. With the tubing used by me, the outside diameter of each additional tube is reduced ¼ inch. The interior diameter of the upper pump chamber is therefore 1¾ inches or an area of 2.405 inches. The annular area of the lower pump chamber is 3/1416 inch less the exterior area of the standing tube 14 which is 1¼ inch in diameter, this leaving a net area of 1.915 which added to the area of the upper chamber gives an effective area of 4.321 inches to be multiplied by the length of stroke in determining the pumping volume, such pumping area and volume being largely in excess of any type of multiple tube pump heretofore known.

In the form shown in Fig. 3 on the up stroke fluid is drawn into the pump through the lower standing valve 45-46, and upward past the auxiliary standing valve 51-52 into the pump chamber. On the down stroke the travelling tubes 31-33 discharge fluid so drawn in, through the openings 22A and the passageway exterior to the tube 50 against the lower standing valve 45-46 and thence upward through the auxiliary standing valve 51-52, and outward through the passageways 54 into the passageways 55-56 which lead upward within the tubing 10, and at the same time the standing tubes 13-14 acting on the upper chamber 37 of Fig. 1, force the liquid within such chamber upward through the travelling valve 26-27 and discharge this fluid through the case 28, likewise into the tubing 10, the effective pumping displacement being the same as before.

In this latter type of pump should the pump acceleration be excessive, fluid held in the pressure release assembly by the lower standing valve will raise the auxiliary standing valve and escape through the passageways 54 into the tubing. On the up stroke this latter valve will immediately close holding the fluid in the tubing. Also, since on downward movement of the plunger flow is through the passageway 54 directly into the bottom of the tubing, sand will effectively be prevented from settling, thereby keeping the pump from silting up between the outside of the tube assembly and the inside of the tubing.

At any time the entire pump assembly may be withdrawn from the well, as for inspection and/or repair, by withdrawing the sucker rod 30.

What I claim is:

1. In a pump having a discharge pipe with an annular seat adjacent its lower end, a cylinder assembly and a plunger assembly reciprocably cooperating; said cylinder assembly including an annular head adapted to be removably supported by said seat, said head including a standing valve discharging upwardly, two spaced and concentric standing tubes secured to said head and extending upwardly therefrom, an annular spacer secured and sealed around the upper end of the inner of said tubes and a shorter standing tube disposed intermediate said two standing tubes, secured and sealed to said spacer and depending therefrom; said plunger comprising an annular head, carrying a travelling valve discharging upwardly, a travelling tube secured to said head and depending therefrom, between and having a working fit with the outer and intermediate ones of said standing tubes, an annular spacer secured within and sealed to said travelling tube at the lower end thereof, and a shorter travelling tube secured within and sealed to said spacer, said shorter tube extending upward between said inner and intermediate standing tubes and having a working fit with both thereof, the lower end of said two travelling tubes and the spacer therebetween forming an annular plunger in the annular chamber between the said inner and the outer of said standing tubes, said inner standing tube having openings establishing free communication from said chamber into the bore of said inner standing tube.
2. In a pump, a discharge pipe, a cylinder assembly and a plunger assembly reciprocably cooperating; said cylinder assembly comprising an annular head supported by said discharge pipe, said head including a standing valve discharging upwardly, two spaced and concentric standing tubes secured to said head and extending upwardly therefrom, an annular spacer secured and sealed around the upper end of the inner of said tubes and a shorter standing tube disposed intermediate said two standing tubes, secured and sealed to said spacer and depending therefrom; said plunger comprising an annular head, carrying a travelling valve discharging upwardly, a travelling tube secured to said head and depending therefrom, between and having a working fit with the outer and intermediate ones of said standing tubes, an annular spacer secured within and sealed to said travelling tube at the lower end thereof, and a shorter travelling tube secured within and sealed to said spacer, said shorter tube extending upward between said inner and intermediate standing tubes and having a working fit with both thereof, the lower end of said two travelling tubes and the spacer therebetween forming an annular plunger in the annular chamber between the said inner and the outer of said standing tubes, said inner standing tube having openings establishing free communication from said chamber into the bore of said inner standing tube.

3. In a pump having a discharge pipe with an annular seat adjacent its lower end, a cylinder assembly and a reciprocably cooperative plunger assembly; one said assembly including three uniformly spaced concentric tubes, and the other assembly two tubes nesting and having a working fit with said three tubes, a head secured to contiguous ends of the outer and inner of said three tubes and sealing the annular space between said tube ends, means securing together the opposite ends of said inner tube and the intermediate of said tubes and sealing the annular space between said ends, a head secured to the outer of said two tubes at the end remote from said first head, means secured to the opposite ends of said two tubes and sealing the annular space between said ends, said heads each having an opening therethrough and a one way valve closure therefor, and both of said closures opening upward; one of said heads being securable at its upper end to a pump sucker rod, and the other thereof having supporting means adapted to seat on said annular seat.
4. In a pump having a discharge pipe with an annular seat adjacent its lower end, a cylinder assembly and a plunger assembly reciprocably cooperating, said cylinder assembly comprising a head adapted to be supported by said seat, two spaced standing tubes secured to said head and extending upwardly therefrom, the inner of said tubes having openings therethrough adjacent said head, and having an annular spacer secured and sealed around its upper end, and a shorter standing tube disposed intermediate said first tubes, secured and sealed to said spacer and depending therefrom; said head having an upper portion forming a closure for the lower ends of said inner and outer standing tubes, and concentric annular downward extensions therefrom, said extensions each carrying a standing valve discharging upward, said upper head portion being apertured to establish a passageway from the inner of said extensions above its said valve into said well tubing, and being independently apertured to establish connection from the outer of said extensions above its said valve into the space between said inner and outer standing tubes; said plunger comprising a head carrying a travelling valve discharging upwardly, a travelling tube secured to said head and depending therefrom, between and having a working fit with the outer of said standing tubes and said intermediate tube, a spacer secured within said travelling tube at the lower end thereof, and a second tube shorter than said first tube secured within said spacer, and extending upward between said inner and intermediate standing tubes and having a working fit with both thereof, the lower end of said travelling tubes and spacer forming an annular plunger cooperating with walls of said inner and outer standing tubes.

CLIFFORD M. PETERS.
